[57] ABSTRACT

Quaternary ammonium compounds of the formula

in which R, R₁, R₂, R₃, A and X have the meaning given in the disclosure and a process for their preparation. The quaternary ammonium compounds are excellent dyeing auxiliaries in dyeing with cationic dyestuffs fibre materials which can be dyed with cationic dyestuffs.

11 Claims, No Drawings

X_1 represents chlorine or bromine and n represents 1 or 2.

The reaction is preferably carried out at temperatures of between 30° and 150°C in the presence of organic solvents which are inert towards ester groups, such as acetone, diethyl ether, dioxane, tetrahydrofuran, tert. butanol, formamide, dimethylformamide, dimethylsulphoxide, hydrocarbons or halogenated hydrocarbons. The quaternary ammonium compounds according to the invention are obtained, if necessary after distilling off the solvent, as watersoluble crystalline products and in some cases also as noncrystallising syrups or resins.

The carboxylic acid esters of the formula (II) can be manufactured in accordance with known processes from carboxylic acids or their derivatives and hydroxylalkylamines, preferably by reaction of lower alkyl esters of the carboxylic acids with hydroxylalkylamines. The following esters of the formula (II), for example, can be employed for the manufacture of the quaternary ammonium compounds according to the invention: caprylic acid 2-dimethylaminoethyl ester, 2-ethylhexanoic acid 2-dimethylaminoethyl ester, capric acid 2-diethylaminoethyl ester, lauric acid 2-dimethylaminoethyl ester, lauric acid 2-dimethylamino-isopropyl ester, lauric acid 3-dimethylamino-propyl ester, lauric acid 2-dibutylamino-ethyl ester, myristic acid 2-dimethylamino-ethyl ester, myristic acid 2-diethylamino-ethyl ester, myristic acid 2-(N-morpholino)-ethyl ester, palmitic acid 2-dimethylaminoethyl ester, palmitic acid 2-dimethylamino-isopropyl ester, palmitic acid 3-diethylamino-propyl ester, palmitic acid 2-(N-piperidyl)-ethyl ester, stearic acid 2-dimethylaminoethyl ester, stearic acid 2-diethylamino-ethyl ester, stearic acid 2-dimethylamino-isopropyl ester, stearic acid 3-dimethylamino-propyl ester, stearic acid 2-dibutylaminoethyl ester, stearic acid 2-(N-pyrrolidinyl)-ethyl ester, stearic acid 2-[bis-(β -hydroxypropyl)amino]-ethyl ester, arachidic acid 2-dimethylamino-ethyl ester, arachidic acid 2-diethylamino-ethyl ester, behenic acid 2-dimethylaminoethyl ester, undecylic acid 2-dimethylamino-ethyl ester, undecylenic acid 2-dibutylamino-ethyl ester, hexadecenoic acid 2-dimethylamino-ethyl ester, oleic acid 2-dimethylaminoethyl ester, linoleic acid 2-diethylaminoethyl ester, cyclohexanecarboxylic acid 3-diethylamino-propyl ester, dimethylcyclohexanoic acid 2-dibutylamino-ethyl ester, decahydronaphthalene-carboxylic acid 2-dimethylamino-ethyl ester, abietic acid 2-dimethylamino-ethyl ester, benzoic acid 2-dimethylamino-ethyl ester, naphthoic acid 2-dimethylaminoethyl ester, phenylacetic acid 2-dimethylamino-ethyl ester, phenoxyacetic acid 2-dibutylamino-ethyl ester and nonylphenoxyacetic acid 2-dimethylamino-ethyl ester.

The halogenomethylation products of the formula (III) can be manufactured in a manner which is in itself known, for example by reaction of compounds containing at least 2 isocyclic rings with formaldehyde and hydrochloric acid or hydrobromic acid. Compounds of the formula (III) which are suitable for the manufacture of the quaternary ammonium compounds according to the invention are, for example: 1-chloromethyl-naphthalene, 2-chloromethyl-naphthalene,

1-bromomethylnaphthalene, bis-chloromethyl-naphthalene, 2-chloro-methyl-tetrahydronaphthalene, bis-chloromethyl-tetrahydronaphthalene, 1-chloromethyl-4-methyl-naphthalene, 1-chloro-methyl-4-chloronaphthalene, 4-chloromethyl-diphenyl-ether, 4-bromomethyl-diphenyl-ether, 4,4'-bis-chloromethyl-diphenylether, chloromethyl-ditolyl-ether, bis-chloromethyl-ditolylether, chloromethyl-chlorodiphenyl-ether, chloromethylnitrodiphenyl-ether, chloromethyl-dibenzyl-ether, bischloromethyl-dibenzyl-ether, 3-chloromethyl-2,4,6-trimethylbenzophenone, chloromethyl-biphenyl, bis-chloromethylbiphenyl, 4-chloromethyl-cyclohexylbenzene, chloromethyldiphenylmethane and chloromethyl-2,2-diphenylpropane.

The quaternary ammonium compounds according to the invention, of the formula (I), can furthermore be manufactured by esterification of amines of the formula

in which

$\text{R}_1, \text{R}_2, \text{R}_3, \text{A}$ and X^- have the abovementioned meaning, with carboxylic acids of the formula

in which

R has the abovementioned meaning, or their functional derivatives capable of ester formation, such as methyl esters, phenyl esters, acid amides, acid chlorides or acid anhydrides.

The compounds according to the invention are surfaceactive products. They have proved particularly valuable as auxiliaries when dyeing, with cationic dyestuffs, fibre materials which can be dyed with cationic dyestuffs.

The dyeing of the fibre materials which can be dyed with cationic dyestuffs can be carried out in the customary manner, by introducing the material to be dyed into an aqueous dyeing liquor, warmed to about 50° - 60°C, which contains the cationic dyestuff, compounds of the formula (I), added salts, such as sodium acetate or sodium sulphate, and also acids, such as acetic acid or formic acid, subsequently raising the temperature of the dyebath to about 100°C over the course of about 30 minutes and then keeping the dyebath at this temperature until it is exhausted. It is also possible to pre-treat the material to be dyed, at a temperature of 40° - 100°C, with a liquor which contains the customary salts and acids as well as compounds of the formula (I), but as yet does not contain any dyestuff, to add the dyestuff only at this stage and to carry out the dyeing at 100°C. Finally, it is also possible to introduce the material to be dyed directly into the dyebath, heated to about 100°C, which contains compounds of the formula (I).

Possible cationic dyestuffs are dyestuffs of the most diverse classes of compounds, for example diphenyl-

methane, triphenylmethane and rhodamine dyestuffs, azo or anthraquinone dyestuffs containing onium groups, and also thiazine, oxazine, methine and azomethine dyestuffs such as are described, for example, in Ullmanns Encyclopadie der technischen Chemie (Ullmanns Encyclopedia of Industrial Chemistry), 3rd Edition, 1970, Supplementary Volume, page 225.

The requisite amounts of the compounds of the formula (I) to be used according to the invention can be determined easily by preliminary experiments. In general, amounts of approx. 0.25 to 2.5% of these compounds, relative to the weight of the material to be dyed which has been introduced, are employed.

Possible fibre materials which can be dyed with cationic dyestuffs are, for example, those of anionically modified polyesters and polyamides, but especially

those of polyacrylonitrile or copolymers containing acrylonitrile.

Suitable copolymers containing acrylonitrile are, for example, copolymers of acrylonitrile with vinyl chloride, vinylidene chloride, vinyl acetate, vinyl chloroacetate, vinyl alcohol, acrylic and methacrylic acid, acrylic and methacrylic acid esters, allyl chloroacetate or basic vinyl compounds, such as vinylimidazole, vinylbenzimidazole, vinylpyridine, vinylmethylpyridine and vinylpyrimidine, provided the proportion of these co-monomers does not exceed 20 per cent by weight.

As examples of quaternary ammonium compounds suitable for the dyeing process, those compounds of the formula (I) in which R, R₁, R₂, R₃, A—CH₂— and X⁻ have the meaning indicated in the table below may be mentioned.

TABLE

	R	R ₁	R ₂	R ₃	A—CH ₂ —	X
1.	C ₉ H ₁₉	-C ₂ H ₄ -	CH ₃	CH ₃	Naphthyl-(1)-methyl-	Cl ⁻
2.	C ₁₁ H ₂₃	-C ₂ H ₄ -	CH ₃	CH ₃	"	Cl ⁻
3.	C ₁₁ H ₂₃	-C ₃ H ₆ -	CH ₃	CH ₃	"	Br ⁻
4.	C ₁₁ H ₂₃	-C ₂ H ₄ -	C ₂ H ₅	C ₂ H ₅	"	HSO ₄ ⁻
5.	C ₁₁ H ₂₃	-C ₄ H ₈ -	CH ₃	CH ₃	"	I ⁻
6.	C ₁₁ H ₂₃	-C ₂ H ₄ -	CH ₃	CH ₃		Cl ⁻
7.	C ₁₅ H ₂₇	-C ₂ H ₄ -	CH ₃	CH ₃	Naphthyl-(1)-methyl-	Cl ⁻
8.	C ₁₅ H ₂₇	-C ₂ H ₄ -	CH ₃	CH ₃	4-Chloronaphthyl-(1)-methyl-	Cl ⁻
9.	C ₁₅ H ₂₇	-C ₂ H ₄ -	C ₄ H ₉	C ₄ H ₉	Naphthyl-(1)-methyl-	Cl ⁻
10.	C ₁₅ H ₃₁	-C ₂ H ₄ -	CH ₃	CH ₃	"	Br ⁻
11.	C ₁₅ H ₃₁	-C ₃ H ₆ -	CH ₃	CH ₃	4-Cyclohexyl-benzyl	Cl ⁻
12.	C ₁₅ H ₃₁	-C ₂ H ₄ -	CH ₃	CH ₃	4-Methylnaphthyl-(1)-methyl-	Cl ⁻
13.	C ₁₅ H ₃₁	-C ₂ H ₄ -	CH ₃	CH ₃	4-Phenoxy-benzyl-	Cl ⁻
14.	C ₁₅ H ₃₁	-C ₂ H ₄ -	CH ₃	CH ₃		Cl ⁻
15.	C ₁₅ H ₃₁	-C ₂ H ₄ -	CH ₃	CH ₃	4-Phenyl-benzyl-	CH ₃ OSO ₃ ⁻
16.	C ₁₇ H ₃₅	-C ₂ H ₄ -	CH ₃	CH ₃	Naphthyl-(1)-methyl-	
17.	C ₁₇ H ₃₅	-C ₂ H ₄ -	CH ₂ CH ₂ OH	CH ₂ CH ₂ OH	"	Br ⁻
18.	C ₁₇ H ₃₅	-C ₂ H ₄ -	CH ₂ CH ₃	CH ₂ CH ₃	"	Cl ⁻
19.	C ₁₇ H ₃₅	-C ₃ H ₇ -	CH ₃	CH ₃	4-Chloronaphthyl-(1)-methyl-	Cl ⁻
20.	C ₁₇ H ₃₅	-C ₂ H ₄ -	CH ₃	CH ₃	Tetrahydronaphthyl-(2)-methyl-	Cl ⁻
21.	C ₁₇ H ₃₅	-C ₂ H ₄ -	CH ₃	CH ₃	4-Phenoxy-benzyl-	Cl ⁻

TABLE—Continued

	R	R ₁	R ₂	R ₃	A-CH ₂ -	X
22.	C ₁₇ H ₃₅	-C ₂ H ₄ -	CH ₃	CH ₃	-CH ₂ - -O- -(+)-CH ₂ -N(CH ₃) ₂ CH ₂ OCO-C ₁₇ H ₃₅	Cl ⁻
23.	C ₁₇ H ₃₅	-C ₂ H ₄ -	CH ₃	CH ₃	4-Phenyl-benzyl	Cl ⁻
24.	C ₁₇ H ₃₅	-C ₂ H ₄ -	CH ₃	CH ₃	-CH ₂ - -(+)-CH ₂ -N(CH ₃) ₂ CH ₂ OCO-C ₁₇ H ₃₅	Cl ⁻
25.	C ₁₇ H ₃₅	-C ₂ H ₄ -	CH ₃	CH ₃	4-Benzyl-benzyl-	Br ⁻
26.	C ₁₇ H ₃₅	-C ₂ H ₄ -	CH ₃	CH ₃		Cl ⁻
27.	C ₁₉ H ₃₉	-C ₂ H ₄ -	CH ₃	CH ₃	Naphthyl-(1)-methyl-	Cl ⁻
28.	C ₂₁ H ₄₃	-C ₂ H ₄ -	CH ₃	CH ₃	"	CH ₃ COO ⁻
29.	C ₁₀ H ₁₉	-C ₂ H ₄ -	CH ₃	CH ₃	"	CH ₃ OSO ₃
30.	C ₁₇ H ₃₃	-C ₂ H ₄ -	CH ₃	CH ₃	Naphthyl-(1)-methyl-	HSO ₄ ⁻
31.	C ₁₇ H ₃₃	-C ₂ H ₄ -	CH ₃	CH ₃	4-Phenoxy-benzyl-	Cl ⁻
32.	C ₁₇ H ₃₃	-C ₂ H ₄ -	CH ₃	CH ₃	-CH ₂ - -(+)-CH ₂ -N(CH ₃) ₂ CH ₂ OCO-C ₁₇ H ₃₃	Cl ⁻

As examples of further compounds to be used according to the invention, the following may be mentioned:

play a considerably increased activity, so that it is possible to work with substantially lower amounts of auxiliary. The increased activity is of importance above all

With the aid of the quaternary ammonium compounds of the formula (I) according to the invention it is possible to dye fibre materials which in particular consist of polyacrylonitrile or copolymers containing acrylonitrile or containing such polymers or copolymers, these fibre materials being in the most diverse states of processing, for example as tows, top, flocks, filaments, yarns, woven fabrics or knitted fabrics, particularly uniformly and in deep shades.

Compared to the quaternary ammonium compounds usually employed in dyeing polyacrylonitrile with cationic dyestuffs, the compounds of the formula (I) dis-

60 when dyeing with dyestuffs of high affinity, that is to say dyestuffs which are absorbed very rapidly, since in that case the known retarders must be employed in large amounts in order to achieve level dyeings. It is noteworthy that the compounds do not lower the capacity of the fibres to absorb the cationic dyestuffs and that the compounds additionally impart a pleasant soft handle to the dyed materials.

EXAMPLE 1

71 g of stearic acid 2-dimethylamino-ethyl ester, prepared by reacting stearic acid methyl ester with dime-

thylaminoethanol in the presence of titanium tetrabutylate, are dissolved in 150 ml of tetrahydrofuran. The solution is slowly mixed with 35 g of 1-chloromethyl-naphthalene and the whole is stirred for 2 hours at 70° - 80°C. After cooling the reaction mixture, the precipitate is filtered off. The quaternary ammonium compound is obtained in almost quantitative yield in the form of a white, water-soluble crystal powder. After recrystallisation from methylene chloride/acetone, the compound sinters at 90°C and melts at 140° - 142°C.

EXAMPLE 2

65 g of palmitic acid 2-dimethylamino-ethyl ester are dissolved in 150 ml of acetone. The solution is mixed with 36 g of 2-chloromethyl-tetrahydronaphthalene and the whole is heated to the boil for 2 hours. After cooling, the reaction mixture is treated with ether and the reaction product which has precipitated is filtered off. The quaternary ammonium compound is obtained in the form of a white, water-soluble crystal powder. Melting point (after recrystallisation from methylene chloride/acetone): 160° - 162°C.

EXAMPLE 3

71 g of stearic acid 2-dimethylamino-ethyl ester are dissolved in 150 ml of tetrahydrofuran. The solution is slowly mixed with 43 g of monochloromethyl-diphenyl-ether and the whole is stirred for 2.5 hours at 70° to 80°C. After cooling, the reaction product which has precipitated is filtered off and rinsed with acetone. The quaternary ammonium compound is obtained in the form of water-soluble, white crystals which after recrystallisation from methylene chloride/acetone sinter at 65°C and melt at 152° - 153°C.

EXAMPLE 4

71 g of stearic acid 2-dimethylamino-ethyl ester are dissolved in 150 ml of tetrahydrofuran. The solution is slowly mixed with 26.6 g of bis-chloromethyl-diphenyl-ether at 70°C. The mixture is stirred for 3.5 hours at 70° - 80°C and is then treated with 150 ml of acetone at 60°C. After cooling, the reaction product which has precipitated is filtered off. The quaternary ammonium compound is obtained in the form of water-soluble white crystals. Melting point (after recrystallisation from methylene chloride/acetone): 172° - 182°C.

EXAMPLE 5

54 g of lauric acid 2-dimethylamino-ethyl ester are dissolved in 90 ml of tetrahydrofuran. The solution is slowly mixed with 35 g of 1-chloromethyl-naphthalene and the whole is stirred for 3 hours at 70° - 80°C. The reaction product is precipitated as a pasty mass by adding ether to the reaction mixture, and the supernatant solvent is separated off by decantation. The residue crystallises after brief standing. The crystal paste is filtered off and recrystallised from acetone. The quaternary ammonium compound is obtained in the form of a white, water-soluble powder. Melting point: 90° - 92°C.

EXAMPLE 6

71 g of oleic acid 2-dimethylamino-ethyl ester are dissolved in 100 ml of tetrahydrofuran. The solution is mixed with 35 g of 1-chloromethyl-naphthalene and the whole is stirred for 3 hours at 70 - 80°C. Thereafter

the solvent is distilled off in vacuo. The reaction product is left in almost quantitative yield as a clear, water-soluble, yellowbrown resin.

EXAMPLE 7

Yarns of polyacrylonitrile fibres are introduced, in a liquor ratio of 1:40, into a bath warmed to 80°C which per litre contains 0.125 g of a cationic dyestuff (Colour Index No. 51,005, Volume 3, 2nd Edition, 1956), 0.25 g of sodium acetate, 0.3 g of glacial acetic acid and 0.1 g of the compound of the formula

The bath is heated to 98°C and kept for 60 minutes at 20 this temperature. A uniform, brilliant blue dyeing is obtained. The dyed yarn is distinguished by a pleasant soft handle.

An equally uniform blue dyeing was obtained if instead of the abovementioned compound an equal 25 amount of one of the compounds mentioned in the table under numbers 6, 8, 10, 12, 14, 24, 27, 28, 21 and 22 was used.

EXAMPLE 8

30 Yarns of polyacrylonitrile fibres are introduced, in a liquor ratio of 1:40, into a bath warmed to 80°C which per litre contains 0.5 g of a cationic dyestuff of the formula

0.25 g of sodium acetate, 0.3 g of glacial acetic acid and 0.125 g of the compound of the formula

The temperature of the bath is brought to 98°C and the 50 yarns are treated at this temperature for 60 minutes. A blue dyeing of outstanding uniformity is obtained. The handle of the dyed yarn is pleasantly soft.

An equally level blue dyeing was obtained if instead of the compound mentioned the same amount of one of the compounds mentioned in the table under numbers 4, 5, 11, 13, 14, 15, 18, 20, 23, 26, 31 and 32, or 55 the compound

was used.

EXAMPLE 9

Yarns of polyacrylonitrile fibres are introduced, in a liquor ratio of 1:40, into a bath warmed to 98°C which per litre contains 0.2 g of a cationic dyestuff of the formula

0.25 g of sodium acetate, 0.3 g of glacial acetic acid and 0.15 g of the quaternary compound mentioned in Example 1. The yarns are dyed for 60 minutes at the same temperature. A yarn which is very uniformly dyed red, and which is distinguished by a pleasant soft handle, is obtained.

EXAMPLE 10

Yarns of polyacrylonitrile fibres are introduced, in a liquor ratio of 1:40, into a bath warmed to 80°C which per litre contains 0.1 g of the cationic dyestuff described in Example 8 of British Patent Specification 973,259, 0.25 g of sodium acetate, 0.3 g of glacial acetic acid and 0.35 g of the compound of the formula

The bath is heated to 98°C and kept at this temperature for 60 minutes. A uniform blue dyeing is obtained.

We claim:

1. Quaternary ammonium compound of the formula

in which

R represents a $\text{C}_5\text{--C}_{21}$ -alkyl or -alkenyl radical;

R_1 represents an alkylene radical with 2 to 4 carbon atoms;

R_2 and R_3 independently of one another denote a $\text{C}_1\text{--C}_4$ -alkyl or $\text{C}_1\text{--C}_4$ -hydroxyalkyl group, or together with the nitrogen atom form a heterocyclic ring selected from the group consisting of pyrrolidine, piperidine and morpholine;

A represents a radical containing at least 2 isocyclic rings, selected from the group consisting of naphthyl, γ -naphthyl, tetrahydronaphthyl, γ -tetrahydronaphthyl, 4-methylnaphthyl, 4-chloronaphthyl, phenoxyphenyl, 4- γ -phenoxyphenyl, tolyloxytolyl, γ -tolyloxytolyl, chlorophenoxyphenyl, nitrophenoxyphe- 55 nyl, (benzyloxy-methyl)-phenyl, γ -(benzyloxy-methyl)-phenyl, 2,4,6-trimethyl-3-benzoylphenyl, diphenyl, γ -diphenyl, cyclohexylphenyl, benzylphenyl, and 4-[2-phenyl-propyl-(2)]-phenyl, wherein γ is the radical $[\text{R}-\text{COO}-\text{R}^1-\text{N}^-(\text{R}^2)(\text{R}^3)-\text{CH}_2-]\text{X}^-$, wherein the R's are as defined above; and

X is an anion.

2. Quaternary ammonium compound of claim 1 having the formula

in which

R represents a $\text{C}_5\text{--C}_{21}$ -alkyl radical;

R_1 represents an alkylene radical with 2 to 4 carbon atoms;

R_2 and R_3 independently of one another denote a $\text{C}_1\text{--C}_4$ -alkyl or $\text{C}_1\text{--C}_4$ -hydroxyalkyl group, or together with the nitrogen atom form a heterocyclic ring selected from the group consisting of pyrrolidine, piperidine and morpholine;

A represents a radical containing at least 2 isocyclic rings, selected from the group consisting of naphthyl, γ -naphthyl, tetrahydronaphthyl, γ -tetrahydronaphthyl, 4-methylnaphthyl, 4-chloronaphthyl, phenoxyphenyl, 4- γ -phenoxyphenyl, tolyloxytolyl, γ -tolyloxytolyl, chlorophenoxyphenyl, nitrophenoxyphe- 55 nyl, (benzyloxy-methyl)-phenyl, γ -(benzyloxy-methyl)-phenyl, 2,4,6-trimethyl-3-benzoylphenyl, diphenyl, γ -diphenyl, cyclohexylphenyl, benzylphenyl, and 4-[2-phenyl-propyl-(2)]-phenyl, wherein γ is the radical $[\text{R}-\text{COO}-\text{R}^1-\text{N}^-(\text{R}^2)(\text{R}^3)-\text{CH}_2-]\text{X}^-$, wherein the R's are as defined above; and

X is an anion.

3. Quaternary ammonium compounds according to claim 1, wherein

R represents a $\text{C}_9\text{--C}_{21}$ -alkyl or $\text{C}_9\text{--C}_{21}$ -alkenyl radical;

R_1 represents the ethylene radical;

R_2 and R_3 denote a methyl or ethyl group or together with the nitrogen atom form a pyrrolidine, piperidine or morpholine ring; and

A represents a tetrahydronaphthyl, diphenyl, phenoxyphenyl, benzylphenyl or cyclohexylphenyl radical.

4. Quaternary ammonium compounds according to claim 1, wherein

R represents a $\text{C}_{11}\text{--C}_{19}$ -alkyl or $\text{C}_{11}\text{--C}_{19}$ -alkenyl radical;

R_1 represents the ethylene radical;

R_2 and R_3 represents the methyl group; and

A represents a naphthyl or phenoxyphenyl radical.

5. Quaternary ammonium compounds according to claim 1, wherein

R represents a $\text{C}_{11}\text{--C}_{19}$ -alkyl or $\text{C}_{11}\text{--C}_{19}$ -alkenyl radical;

R_1 represents the ethylene radical;

R_2 and R_3 represent the methyl group; and

A represents a naphthyl or phenoxyphenyl radical which is substituted by the radical $[\text{R}-\text{COO}-\text{CH}_2\text{CH}_2-\text{N}(\text{CH}_3)_2-\text{CH}_2-]\text{X}^-$, wherein R and X are as defined above.

6. Quaternary ammonium compounds according to claim 5, wherein

A represents a naphthyl radical which is substituted by the radical $[\text{R}-\text{COO}-\text{CH}_2\text{CH}_2-\text{N}(\text{CH}_3)_2-\text{CH}_2-]\text{X}^-$, wherein R and X are as defined above.

7. Quaternary ammonium compounds according to claim 5, wherein

A represents a phenoxyphenyl radical which is substituted by the radical $[\text{R}-\text{COO}-\text{CH}_2\text{CH}_2-\text{N}(\text{CH}_3)_2-\text{CH}_2-]\text{X}^-$.

13

$\text{R}_2\text{—CH}_2\text{—}] \text{X}^-$, wherein R and X are as defined above.

8. Compound according to claim 1 wherein R represents a C_{17} -alkyl radical; R_1 represents the ethylene radical; R_2 and R_3 represents the methyl group; and A represents a naphthyl radical.

9. Compounds according to claim 8 wherein A represents a naphthyl radical which is substituted by the radical $[\text{R—COO—CH}_2\text{CH}_2\text{—N}(\text{CH}_3\text{)}_2\text{—CH}_2\text{—}] \text{X}^-$, wherein R and X are as defined above. 10

10. Compounds according to claim 1 wherein R represents a C_{17} -alkyl radical; R_1 represents the ethylene radical; R_2 and R_3 represents the methyl group; and A represents a phenoxyphenyl radical which is substi- 15

14

tuted by the radical $[\text{R—COO—CH}_2\text{CH}_2\text{—N}(\text{CH}_3\text{)}_2\text{—CH}_2\text{—}] \text{X}^-$, wherein R and X are as defined above.

11. Compound according to claim 1 having the formula
